UNITED STATES PATENT OFFICE.

ELLIS M. POTTER, OF NEW YORK, N. Y.

APPLIANCE TO FACILITATE TYING OF NECKTIES.

Application filed August 13, 1921. Serial No. 492,078.

To all whom it may concern:

Be it known that I, ELLIS M. POTTER, a citizen of the United States, and resident of 90 West Broadway, New York city, in the county of New York and State of New York, have invented certain new and useful Appliances to Facilitate Tying of Neckties, of which the following is a specification.

10 My invention relates to improvements in neck-ties generally, more especially to what is termed the four-in-hand type.

The invention has for its object, among other purposes, principally to obviate the necessity of tying or forming the knot each time the tie is worn.

A further object is to provide for facilitating the application of the tie for use.

Still another object of my invention is 20 to provide a form upon which the knot is made, the same being so constructed and shaped that when the tie is in use it is not distinguishable from a tie the knot of which is formed by hand in the usual manner.

Another object of my invention is to provide a form upon which the knot is made having a passage therethrough for the free or smaller end portion of the tie after the same passes around the neck of the wearer.

Other objects of the invention will be apparent from the following description, and by reference to the accompanying drawings, in which:—

35 Figure 1 is a front view of my improved device with a four-in-hand type of tie applied thereto, and with portions of the form or device and tie cut away for clearness.

Figure 2 is a rear view of Figure 1 with 40 the free end portion of the tie uninserted within the form, and with a portion of the tie cut away to disclose the rear structure of the form, and

45 Figure 3 is an enlarged view of the form with the tie removed therefrom, the same illustrating its rear structure.

Referring to the accompanying drawings in detail, wherein like reference characters denote corresponding parts throughout the 50 several views, the numeral 1 designates a tubular body portion or member formed of suitable metal, the lower end portion of which has formed integral therewith a

downwardly pointed projection 2 upon which the smaller end portion A' of a tie 55 A is adapted to be impaled or caught, after the same passes through the tubular member 1, as disclosed in the drawings and hereinafter described.

The upper end portion of the tubular 60 member 1 is somewhat enlarged to form substantially a T-shaped head, the same being cut in a vertical plane to provide a front face 3 and a rear face 4, the latter being folded back, upon a slanting line, over the 65 main body 1, or a portion thereof.

That portion of the form where the front face 3 and the rear face 4 substantially meet have formed therebetween an opening 5, through which the free end portion A' of 70 the tie is adapted to be inserted, as herein-after described.

In applying a tie of the type referred to upon my improved form, the rear face portion of the tie is placed upon the rear 75 face 4 of the form, the same being applied thereto somewhat near that part of the tie where the knot is desired. In forming the knot, the enlarged end portion of the tie is then wrapped around the front face of 80 the form, passing under the smaller portion, over the same and down between the front face of the form and the body of the tie. The enlarged end portion is then pulled down snugly upon the form, thus giving 85 a correct appearance to the knot. The tie in this condition is now ready for use and it will be noted that the form is retained within the knot of the tie at all times.

In using the tie, the smaller end portion 90 thereof is passed around the neck of the wearer and inserted through the opening 5 and down through the tubular member 1, where a slight pull upon the smaller end portion will cause the knot to fit snugly 95 against the collar, the same being retained in that position by means of the projection 2 engaging a portion of the smaller end.

From the foregoing, it is thought that the 100 construction, operation and many advantages of the herein described invention will be apparent to those skilled in the art, without further description, and it will be understood that various changes in the size, shape, proportion and minor details of construction 105 may be resorted to without departing

from the spirit or sacrificing any of the advantages of the invention.

Having thus fully described my invention, what I claim as my invention is:

5 An article of the class described formed of a tubular body portion having an enlarged upper end, said end being divided

vertically to form front and rear faces, a bent over portion carried by the rear face and adapted to form a tie retaining element. 10

Signed at New York city, in the county of New York and State of New York, this 5th day of April A. D. 1921.

ELLIS M. POTTER.
